UNITED STATES PATENT OFFICE.

SARA HUMPHREYS WINGO, OF SAN DIEGO, CALIFORNIA, ASSIGNOR, BY DIRECT AND MESNE ASSIGNMENTS, OF ONE-SIXTH TO WILLIAM RELFE HUMPHREYS, ONE-SIXTH TO JOHN K. TAUBMAN, ONE-SIXTH TO MAMIE C. WILSON, AND ONE-SIXTH TO STEPHEN N. WILSON, ALL OF LEXINGTON, MISSOURI.

REVERSIBLE CUFF.

Application filed October 1, 1921. Serial No. 504,685.

To all whom it may concern:

Be it known that I, SARA H. WINGO, a citizen of the United States, and a resident of San Diego, in the county of San Diego and State of California, have invented certain new and useful Improvements in Reversible Cuffs, of which the following is a specification.

This invention relates to improvements in 10 cuffs for shirts, shirtwaists and the like, and has reference more particularly to cuffs of the kind commonly known as "French" cuffs, and is more especially designed for use with shirts of soft material such as silk, madras, 15 soft linen and the like, and which are not usually intended to be starched, or at least but slightly starched, so that they may be folded without breaking or cracking along the line of fold.

20 The object of the invention is to provide a novel and improved cuff of the kind specified, which is reversible, that is to say, a cuff intended preferably to be permanently attached to the sleeve and in which the fold 25 of the cuff may be turned or reversed outwardly twice and once within the sleeve, as desired.

Among the advantages derived from its 30 novel construction by which it has the same appearance whether it is folded normally or reversed: it is without uncomfortable or unsightly bulk in either normal or reversed folding; and it may be manufactured at 35 greatly reduced cost as compared with the reversible cuffs as heretofore produced.

With the above stated and other objects and advantages in view the invention consists in certain novel features of construction, arrangement and combination of parts 40 as will be hereinafter fully described and pointed out in the claims, reference being had to the accompanying drawings forming a part hereof and in which:

Figure 1 is a perspective view illustrating 45 my reversible cuff fixed to a shirt sleeve, and when normally folded, that is, folded outwardly upon itself,

Figure 2 is a similar view showing the 50 position preparatory to making the first reversal,

Figure 3 is a vertical sectional view on line 3—3 Figure 1 on a larger scale, through the cuff and associated sleeve,

Figure 4 is a longitudinal section of the invention in the stage illustrated in Figure 2,

Figure 5 is a perspective view of the cuff as a separate unit,

Figure 6 is a perspective view of a modified form.

Figure 7 is a section on the line 7—7 of Figure 5.

In the drawings, the numeral 8 indicates a sleeve which may be assumed to be the sleeve of a man's shirt. The cuff is made of 65 two plies of material or folds 9 and 10 which in the present instance may be termed the inner and outer folds respectively, which are of the same size and pattern, and an interlining 11 between them, the interlining being 70 secured between them at the ends. This interlining which may be of the same material as the folds, but preferably of an inferior fabric, is of less depth or width than the inner and outer folds extending only to 75 about the longitudinal median line X of the cuff before initial folding, and is stitched or basted to the one of the folds usually the inner, along that line. The ends of the inner and outer folds and the ends of the interlining are all sewed together preferably 80 by a "French" seam which permits the reversing to show the same appearance of seam.

The lower ends of the inner and outer 85 folds or plies are also preferably connected by a French seam. The usual button holes 13 in the upper portions of the cuff are cut through the inner and outer plies and the interlining and the stitching that reinforces 90 these button holes attaches all of the parts together.

14 indicates the other button holes in the cuff placed in the usual way, and in these button holes the stitching that reinforces 95 the holes attaches the inner and outer folds of the cuff together. These latter button holes 14 are adapted to register with the button holes 13 when the cuff is folded upon itself, either inwardly or outwardly.

15 indicates a flap or ply of material of 100 the same pattern as the other two plies, but is of less width being seamed at its lower edge and ends to the cuff body composed of the inner and outer folds, this flap 15 lying 105 against the outer face of the outer ply and

its upper longitudinal edge 16 being entirely unconnected with the cuff body except at its extreme ends; this free upper edge extends somewhat above the longitudinal center or 5 median line of the cuff, and has button holes 17 which register with the button holes 13 of the cuff body. The lower ends of this outer flap 15 also has button holes 18 and these register with the button holes 14 of the 10 cuff body, but the button holes of the flap 15 are not stitched through and connected with the cuff body.

The lower edge and the two ends of the flap 15 may be secured to the cuff body by 15 the same "French" seaming that unites the two plies of the cuff body, but is not absolutely essential. The upper end of the flap 15 may be hemmed as shown at 21, but this also is not absolutely essential.

20 It will be seen from the foregoing that an open or patch pocket 19 is formed on the cuff body, the purpose and office of which will be presently set forth.

The article thus far described constitutes 25 a complete reversible and double wear cuff and may be sold this way either for sewing to a shirt sleeve or attaching to the same by mechanical means, such as clasps and the like.

30 However the more usual way of utilizing the invention will be to stitch them to the shirt sleeves and this will be done by folding inwardly the upper ends of the inner and outer plies and the interlining inserting the 35 lower end of the sleeve and stitching through all of them as indicated by the numeral 19' in Figures 1, 2, 3 and 4.

The first "wear" of the cuff is had with 40 the cuff in the condition indicated in Figure 1. Now should it be desired to "reverse" the cuff, buttons 20 are removed and the outer fold allowed to assume the position shown in Figures 2 and 4. To reverse the cuff, hold each end of cuff in hands; open 45 the turned over part inserting the thumbs under the extra piece or ply 15 turning the same over the fingers onto the inside of the cuff, a little care being necessary to effect a smooth turning; then turn cuff back onto the original fold and replace cuff button. To get a third "wear" just reverse the original fold, that is, turn the fold inwardly, instead of outwardly as formerly.

50 The cuff need not be provided with button holes and will function readily with the ordinary link button substitutes, or outer clamps or "hold-tight" bars, such a modified form of cuff being shown in Figure 6.

I claim:-

60 1. A cuff of the character specified, and comprising a body portion consisting of two plies of the same size and pattern stitched together at their ends and at their lower longitudinal edges, and a third ply of less 65 depth united at its ends and lower longitudi-

nal edge to the outer face of one of said first named plies, said first named plies having alined and connecting button holes adjacent their ends in their upper and lower portions, the third ply also having button 70 holes adjacent its two ends so positioned as to register or aline with the button holes of the first named two plies, the upper longitudinal edge of the third ply free from the underlying or subjacent ply of the first 75 named pair from end to end, whereby a pocket is formed adapted to be turned and overlying the other ply of the first named pair, the upper longitudinal edges of the first named plies adapted to be stitched to 80 the lower end of a shirt sleeve.

2. A cuff of and for the character specified, comprising a pair of plies of the same size and pattern stitched together at their ends and at their lower longitudinal edges, 85 and an interlining between the plies of said pair, of the same length therewith, the lower edge of said interlining extending below the longitudinal median line of the cuff body and stitched to one of the aforesaid plies, the 90 upper ends of the plies and interlining adapted to be secured to the lower ends of a shirt sleeve, the two plies and the interlining having alined button holes adjacent their ends stitched through each other and connecting the whole at said ends above said median line, said pair of plies also provided with alined and stitched together button holes adjacent their ends below said median line, and a third ply stitched at its ends and lower longitudinal edge to the outer face of one of said paired plies, and having button 95 holes alined with the second named stitched-through button holes, the upper edge of said third ply extending above the aforesaid median line and free from the subjacent ply except at the extreme ends.

3. The combination with a sleeve of a shirt, of a reversible cuff of the character described, comprising a pair of plies of the 110 same size and pattern stitched to the sleeve, and a third ply of the same length and pattern but of less depth than the other plies, said third ply stitched at its ends and lower edge only, to the outer face of one of the 115 first named plies, said pair of plies and third ply having alined button holes, adjacent their ends and in both their upper and lower portions.

4. A cuff or the like of the character specified, comprising a body portion consisting of two plies of the same size and pattern secured together at their ends and at their lower longitudinal edges, and a third ply of less depth united at its ends and lower longitudinal edge to the outer face of one of said first named plies, the upper longitudinal edge of the third ply entirely free from the subjacent ply of the first named pair except at its extreme ends, whereby an open pocket 120 125 130

is formed adapted to be turned and overlie the other ply of the first named pair.

5. A reversible cuff or the like comprising a body portion and a supplemental strip of material secured at its ends and lower longitudinal edge to the said body portion, the upper longitudinal edge of said supplemental strip entirely free from the body portion except at its extreme ends, whereby

10 an open pocket is formed adapted to be

turned and overlie the opposite face of the body portion.

6. A reversible cuff or the like, comprising a pair of plies of the same size and adapted to be secured to a shirt, and a third 15 ply of the same length, but of less depth than the first named plies, said third ply secured at its ends and lower edge only, to the outer face of one of the first named plies.

SARA HUMPHREYS WINGO.
